PISTON BLANKS

Carl Lehmeier, 315 Sumac Lane, Santa Monica, Calif.
Filed Jan. 25, 1954, Ser. No. 406,007
4 Claims. (Cl. 29—190)

This invention relates to pistons or similar objects of cut shape having an end wall and a skirt or cylindrical wall portion integral therewith, and portions of which are of varying thickness for functional purposes.

Primarily, the invention constitutes a modification of and further disclosure of piston design and punch and die construction which may be utilized in making the piston blanks such as described and claimed in the application of Romaine Elden Watson, John R. Boston, and Carl Lehmeier, Serial No. 35,388, filed June 26, 1948, and now in issue as Patent No. 2,667,390, dated January 26, 1954.

I have found that the die of a piston blank may affect the flow of material from the blank along the surfaces of the die cavity and punch forming the piston blank, and that accurate control of the height of the skirt or wall of the piston, particularly where the skirt has portions of different lengths, may be related to corresponding modifications of the surfaces of the die cavity or those of the punch, or both.

An object of the invention is to facilitate the flow of the metal by single stroke impact extrusion, such as described in the aforementioned application and patent, and to prevent excessive flow above certain desired heights of the skirt portion, while reducing to a minimum the amount of material which may be required to be removed by subsequent machining of the blank for producing the finished piston.

In the joint application of the same inventors, above named Watson, Boston and Lehmeier, Serial No. 42,935, now Patent No. 2,756,876, is also shown an apparatus and a method is described, to which the present invention is related. In the second of said applications is particularly pointed out and described the effect of certain flow controlling bevel surfaces formed on the punch, and by which the rate at which the recesses in the punch are filled by the metal flowing upwardly along the punch, on the impact extrusion stroke, shall be at the same rate as that at which the thinner portion of the wall of the skirt wall is moving.

The present invention is concerned with still further control of metal flow, and by which the open end of the skirt may be held to substantially uniform height, as was done in practicing the joint invention of the above-named applications, and in addition, by which, where desired, the height of the skirt between the bosses may be maintained lower than the height over the bosses, to meet requirements of motor and engine manufacturers using large numbers of such pistons.

Where it is desired to maintain the interior surface of the piston substantially cylindrical and to attain the lightest possible weight of the finished piston, the die cavity may be provided with means which effect both additional retarding of the flow of metal from the end of the punch on the long skirt portion, which, however, leaves the exterior slightly non-cylindrical, and thus requires machining to a slightly greater overall depth.

As an alternative, and which may be carried out without adding materially in fact an extremely small amount of weight, if any, and yet provide for balancing the space of the flow by providing thickened skirt portions between the bosses may be by forming eccentric arcs of the cylindrical surface of the inside of the piston while forming the exterior in a true cylinder and only slightly larger than the desired finished machined piston.

2

In my present modification of the inventions of which I was a joint inventor, as appears in the applications above identified, are illustrated in the accompanying drawings, in which:

5 FIGURE 1 is a plan of a piston blank.

FIGURE 2 is the side elevation of the same.

FIGURE 3 is an axial section through the wrist pin bosses.

10 FIGURE 4 is a similar section at right angles showing the piston blank after machining to the plane of FIGURE 3.

FIGURE 5 is a section through the punch and die cavity showing a slug in position to be extruded, taken on an offset plane.

15 FIGURE 6 is a fragmentary section through the wrist pin boss portion showing the position of the metal when partly extruded.

FIGURE 7 is a section detail through the boss cavity portion of the punch and showing a metal flow impeding element on the die and its relation to the punch.

20 FIGURE 8 is a fragmentary horizontal section through the piston blank and the skirt and one of the bosses showing the effect of this flow impeding element.

25 FIGURE 9 is a plan view partially fragmentary, showing the blank with a cylindrical exterior and thickened portions on the interior between the bosses.

Referring to the piston blank shown in FIGURES 1 to 4 and 8, the head of the piston is indicated at 1, which may be flat or crowned, or of other suitable shape on the exterior and which is shown as slightly concave on the interior. This piston head is joined with a thickened portion forming a ring flange 3 and a substantially cylindrical skirt portion 5, with opposite wrist pin bosses 6 joining the head and extending along and integral with the skirt.

30 In FIGURES 1, 2, 3, and 8 are shown side depressions extending circumferentially for a considerable distance around the zone of the bosses 6 and the exterior, and indicated by the side lines 10 and bottom line 11, and by reason of which the wall 12, above and each way from the bosses, is somewhat thinner than the remaining substantially cylindrical portions of the skirt.

35 In FIGURE 3 it will appear that this depressed surface is shown slightly tapered, extending inwardly, as at 13, from the true cylinder indicated by the broken lines 14. These opposite arcuate depressions are formed by a corresponding projection or pad-like protuberance 40, in the die, the lower edge of which is indicated at 41. The die cavity may be cylindrical except for this protuberance.

40 It will be noted also that the skirt portion 5 rises slightly higher above the boss at 15, than at the depressed or scalloped portions 16 therebetween.

45 Bevels 17 and 18 at the base of the bosses are the result of bevels formed on the punch and which have a choking effect, as particularly described in said joint application Serial No. 42,935, now Patent No. 2,756,876.

50 The finished piston is, of course, machined to present a cylindrical exterior, and suitable piston ring grooves, as at 22, are cut as shown, while the pin bosses are bored, as at 20, to receive the wrist pin.

55 The die is shown as having a bottom surface 30, and a cylindrical surface 31. A punch 35 has its end so formed as to shape the inner face of the piston head and, likewise, has reduced portions 36 to form the ring flange 3 and the boss recesses 38 are formed thereon in FIGURE 5. As noted, the section is taken on an offset plane through a boss cavity and a portion of the punch between the cavities. At the recesses 38 and around the perimeter of the open end are formed bevels 42 and 43, forming the bevels 17 and 18 heretofore referred to.

60 Thus, as a blank B, which is shown as a substantially cylindrical billet or slug, is struck by the punch 35,

which continues its downward movement from that shown in FIGURE 5 to that shown in FIGURE 7, the metal flows into the recesses, the ring flange and the skirt forming spaces rising along with the punch at substantially the same rate during this impact extrusion operation, in the manner particularly described in application Serial No. 42,935. There is a tendency for the material to flow more rapidly in the zone of these bosses, however, I may avoid an excessive or abnormal flow above the same, by using the retarding or choking protuberance pads 40 restrict the escape area between the punch and the wall of the die cavity.

The result is that, if desired, the height of the piston blank at the end of the stroke of the punch may be substantially even, or it may be permitted to flow upwardly somewhat in the high portions 15 with relation to the lower portion 16.

Obviously, this choking control may be used to cause the high portions of the piston skirt, such as at 15, to be formed at any angular position with relation to the bosses, while the low portions, as at 16, would be on opposite sides of the piston between high portions.

As a modification, and for some purposes to be preferred, I may enlarge the escape area between the bosses by forming the inner surface of the skirt eccentric between the bosses. Thus, the portions indicated at 50 may be substantially concentric with offset axes 51, with the radius of the arc, indicated by the arrow 52, such that these eccentric surfaces merge with the thinner portion of the wall 55 in the zone of the bosses.

Inasmuch as the punch obviously is machined to form these inner cylindrical surfaces eccentric to the outer cylindrical surface of the piston skirt, and correspondingly with the inner surface 31 of the die cavity, this modification of the punch is not attempted to be shown.

Correspondingly, it is to be understood that the amount of difference in thickness need only be relatively very slight; for example, ranging from a sixty-fourth or less to a thirty-second, up to perhaps a sixteenth at the most, depending on the size of the piston, whereas in the drawings the contrast is exaggerated for clearness of illustration. Thus, assuming the piston blank is of approximately the size shown in the drawings, the thickness of this thin or choked flow area would be thinner by only a small percentage, for example, a wall of three-sixteenths of an inch would be thinned only by a one thirty-second or three sixty-fourths of an inch. In FIG. 9, the ratio between the thickened and thinned portion is approximately as follows: The thinned portion is two-thirds of the thicker portion between the bosses.

The billet B may be specially formed to provide more metal in line with the boss recesses of the punch. Such a billet may be preformed and of cast material, or of worked alloy, and may, if desired, contain a substantial percentage of silicon; or for some pistons, any suitable alloy may be chosen. The billet may be preformed by a machine process, pre-cast, or it may be pre-hit before subjecting it to the impact extrusion stroke of the punch 35.

While a stripper die of common, well-known construction may be used to guide the punch into the cavity, it has been found desirable to avoid any tendency of the punch to become eccentric, as far as possible, and to this end, I may form a central cavity, as indicated at 60 in broken lines in FIGURE 5, and correspondingly, so shape the punch.

From the foregoing description it will be seen that the escape area or radial width of space, through which the metal passes between the punch surface of the die cavity, may be varied to facilitate control of the flow. The contour, whether flat or scalloped, of the top edge or open end of the piston may be formed by the single stroke extrusion method and to substantially the precise height desired for the finished piston. Thus, machining

work or grinding, if any, at the edge of the skirt is minimized, and no amount of weight of material of any consequence is wasted.

By the variation of wall thickness by eccentric cylindrical surfaces within the skirt, the blank may be formed to a precise external diameter, only very slightly more than that of the finished machined surface fitting into the cylinder.

The invention is concerned at present with piston blanks made of aluminum having a predetermined and desirable alloy content, and the finished piston blanks possess characteristics of great strength whereby the head and walls may be of less thickness than pistons formed by present methods, and with resultant light weight also, as indicated in the applications referred to, superior structural strength is attained by such a method. The modifications here particularly illustrated and described are summarized in the appended claims.

I claim:

20. 1. A piston blank comprised of a single piece of cast metal alloy containing a substantial percentage of silicon having an integral head portion, a ring flange portion, and opposite wrist pin bosses extending from the head and along the skirt portion for a substantial distance in relation to the length of the skirt, and the skirt portion having eccentric surfaces forming radially thinner wall sections at each side of the piston and extending across and each way from the angular segmental zone of the pin bosses and to the open end of the skirt, said thinner wall section being thinner radially than that of the circumferentially intervening wall sections by an amount ranging from a sixty-fourth upto one-sixteenth of an inch.

25. 2. The structure defined in claim 1, in which the eccentric thickened skirt portions are formed on the interior by substantially cylindrical surfaces offset inwardly from parallelism with the adjacent cylindrical exterior of the skirt.

30. 3. A piston blank composed of a single piece of cast per-worked silicon containing metal alloy having an integral head portion, a thickened ring flange portion and opposite wrist pin bosses extending along the head and skirt portions for a considerable distance in relation to the length of the skirt and integral therewith, the skirt portion having segmental areas of relatively thin radial section 35 located on opposite sides of the piston and each being of substantially one-fourth the circumference and extending from the open end of the skirt substantially to the ring flange portion, the relatively thin radial sections being substantially $\frac{1}{64}$ to $\frac{1}{16}$ of an inch less in radial thickness throughout the thin area than that of the adjacent thicker portions of the wall.

35. 4. The piston blank defined in claim 3 in which the relatively thinner sections extend longitudinally to higher points with relation to the head and form scallops on 40 opposite sides of the open edge of the skirt.
